UNITED STATES PATENT OFFICE.

LAURA A. CLIMER, OF CHICAGO, ILLINOIS.

DESIGN FOR A FRUIT-JAR CLAMP.

SPECIFICATION forming part of Design No. 35,614, dated January 28, 1902.

Application filed December 12, 1901. Serial No. 85,698. Term of patent 7 years.

To all whom it may concern:

Be it known that I, LAURA A. CLIMER, a citizen of the United States, residing at Chicago, in the county of Cook and State of Illinois, have invented and produced a new and original Design for a Fruit-Jar Clamp, of which the following is a specification, reference being had to the accompanying drawings, forming a part hereof.

- 10 Figure 1 is a view in side elevation of a fruit-jar clamp of my new and original design; Fig. 2, a plan view of the same; Fig. 3, a bottom plan view of the same, and Fig. 4 a perspective sectional view of the same.
- 15 As shown in the drawings, the leading or material feature of the design consists in a flat bar-form top piece *a* and the downturned ends *a'* at substantially right angles thereto and of approximately the same width as the 20 top *a*, the inner and outer surfaces of the member *a* being curved, as shown in Fig. 3.

Minor features of my design are the central boss *a²*, depending from the under surface of the member *a*, and the slightly-inclined grooves *a³*, with which the members *a'* 25 are provided on their inner surfaces near the lower ends.

An additional minor feature is a boss *a⁴* on the outer surface of one of the members *a'*.

Having described my invention, what I 30 claim as new, and desire to secure by Letters Patent, is—

The design for a fruit-jar clamp, as herein shown and described.

In testimony whereof I have signed my 35 name to this specification in the presence of two subscribing witnesses.

LAURA A. CLIMER.
